UNITED STATES PATENT OFFICE.

JULIUS B. WANTZ, OF CHICAGO, ILLINOIS, ASSIGNOR TO VICTOR ELECTRIC COMPANY, OF CHICAGO, ILLINOIS, A CORPORATION OF ILLINOIS.

ELECTRIC-CURRENT INTERRUPTER.

No. 834,597.

Specification of Letters Patent.

Patented Oct. 30, 1906.

Application filed November 22, 1905. Serial No. 288,577.

To all whom it may concern:

Be it known that I, JULIUS B. WANTZ, a citizen of the United States, residing at Chicago, in the county of Cook and State of Illinois, have invented a new and useful Improvement in Electric-Current Interrupters, of which the following is a specification.

My invention relates to improvement in electric-current interrupters for use more especially in connection with electrotherapeutic apparatus; and my object is to provide a simple and improved device of this class capable of ready adjustment to produce interruptions at any speed throughout a comparatively wide range and with great accuracy with reference to an indicator thereon.

In carrying out my invention I provide a cylinder or body of insulating material mounted in a train of spring-driven gears which terminate in an escapement or governor adjustable in accordance with a dial and pointer or equivalent speed-indicating means to effect the desired speed of rotation of the cylinder, the cylinder being provided with separate peripheral circuit making and breaking contact-points positioned in increasing numbers in parallel annular spaces, to either of which the current may be directed by a particular brush to effect a number of interruptions in each rotation of the cylinder in accordance with the number of contact-points in the particular space.

In the drawings, Figure 1 is a face view of my improved interrupter; Fig. 2, a section through the device on line 2 in Fig. 3 and showing diagrammatically an electric switch and therapeutic electrodes in connection therewith; Fig. 3, a view in side elevation of the mechanism; Fig. 4, a rotary cylinder of insulating material mounted on the shaft of one of the gears of the train and carrying independent series of making and breaking contacts; Figs. 5, 6, and 7, sections taken, respectively, on lines 5, 6, and 7 in Fig. 4; Figs. 8 and 9, sections taken on line 8 in Fig. 3 and showing a pointer in two extreme positions with reference to a dial; and Fig. 10, a broken detailed view of speed-governing mechanism.

The frame of the device comprises a forward plate or disk A and a rear plate or disk B, connected by tie-rods *a* in a manner usual

in clock construction. Attached in spaced relation to the plate A is a dial-plate C.

D is a spring fastened at one end to one of the tie-rods *a* and at its opposite end to an arbor or winding-post *b*, carrying a gear-wheel *c*, forming the first of a train of clock-work gears *d*. The final gear of the train *d* meshes with a pinion *e* on a shaft F, which is the escapement or governor shaft. Fixed to the shaft F, adjacent to or integral with the pinion *e*, is a sleeve *f*. On the forward end portion of the shaft F is a sliding sleeve *g*, having an enlarged portion *h*, forming the hub of a friction-disk *i*. Attached at opposite ends to the parts *f* *h* are thin spring-metal strips *k*, which may be three in number equidistant around the shaft F. The spring-strips are provided midway between their ends with weighting-buttons *l*. Fastened against the inner side of the plate A is a spring-strip G, provided with a friction-head *m*, which bears normally against the inner friction-face of the disk *i*.

Mounted between the plates A C in the positions shown and extending through the latter plate is a fixed internally-threaded sleeve *n*, through which passes a screw *H*, bearing normally against the strip or brake-spring G. The screw *H* is connected at its outer end, by means of a set-screw *p*, with a concave disk *l*, having in its face a pointer-mark *q*. Integral with the disk is a milled thumb-piece *r*, by means of which the pointer-disk may be turned to advance or retract the screw *H*. On the face-plate C around the pointer-disk *l* is marked a dial K, the graduated scale of which may be as shown. The disk *l* carries a pin or stop *s*, and fastened to the plate C is a stop-pin *t*, against opposite sides of which the pin *s* will contact in the two extreme positions of the pointer *q*.

The spring D when wound tends to move the train of gears *d* and rotate the escapement or governor shaft F. The parts are so arranged that when the pointer *q* is turned to the figure "0" of the dial the screw *H* is retracted sufficiently to cause the friction-head *m* of the brake-spring G to press firmly against the inner friction-face of the disk *i* and prevent rotation of the governor-shaft, thus stopping movement of the train of gears. Turning of the pointer along the graduated scale or dial K forces the spring G in the in-

ward direction to carry its friction-head *m* away from the disk *i*. The governor-shaft *F* being thus freed rotates, and as its speed increases the weights *l* are thrown out by centrifugal force, thereby contracting the springs *k* until the disk contacts again with the friction head or brake *m*.

The governing mechanism described operates in a well-known manner to regulate the speed of rotation of the escapement-shaft *F*, and consequently the relative speeds of rotation of the gears of the train *d*. In the present instance the adjustment may be such that when the pointer is turned to figure "1" the shaft *L* in the train of gears will rotate twenty-five times per minute and increase by steps according to the dial *K* until when the pointer *q* reaches figure "9" the said shaft will rotate ninety-five times per minute. As shown in Fig. 9, when the pointer is at "9" the stop *s* contacts with the stop *t* to prevent further increase of speed.

Mounted on the shaft *L* of the train of gears is a body or cylinder *M* of insulating material, provided in the present instance with three annular ridges *v w x*. Extending from the shaft *L* to the periphery of the ridge *v* is a contact point or pin 12. Extending from the shaft *L* to the periphery of the ridge *w* are two contact-pins 13, and extending from the shaft *L* to the periphery of the ridge *x* are six contact-pins 14.

N is a block or plate of insulating material fastened to the plate *A* and forming a support for three spring-contacts or brushes 15, 16, and 17, which bear, respectively, against the ridges *v w x*.

P is an electric switch having a handle 18 and contacts 19, 20, and 21. The contact 19 is wired to the contact-spring 15, the contact 20 to the contact-spring 16, and the contact 21 to the contact-spring 17. Wires 22 may extend, respectively, from the handle or switch-lever 18 and any part of the casing of the train of gears and carry suitable electrodes 23.

As before stated, the shaft *L*, and consequently the cylinder *M*, rotates at the speed designated by the dial. When the switch-lever is moved to the contact 19, current will pass through the contact-spring 15, causing the pin 12 to make and break the current once in each revolution of the cylinder. When the handle is turned to the contact 20, the current will pass through the contact-spring 16, causing the pins 13 to make and break the current twice with each revolution of the cylinder *M*, and when the switch-handle is moved to the contact 21 the current will pass through the contact-spring 17, causing the pins 14 to make and break the current six times with each revolution of the cylinder *M*. A table Q on the dial-plate indicates to the operator the number of interruptions per minute obtained in the various

adjustments. For example, when the switch-lever is turned to the contact 19 and the pointer *q* is turned to "1" twenty-five interruptions per minute will occur. While the switch-handle remains at the contact 19, the pointer may be turned to cause the brake mechanism to effect increases in speed of rotation and consequent interruption in accordance with the first line of figures of the table Q. Turning of the switch-handle to the contact 20 gives twice the number of interruptions of the first table, and movement of the switch-handle to the contact 21 produces six times the number of the first table, whereby any number of interruptions per minute between twenty-five and five hundred and seventy may be produced with at least reasonable accuracy.

What I claim as new, and desire to secure by Letters Patent, is—

1. In an electric-current interrupter, the combination with a frame and speed-indicator, of a train of gears with actuating means therefor mounted in the frame, a body of insulating material operatively connected with the gears to be rotated thereby, a current making and breaking contact on said body, a brush against which said body rotates to cause the contact thereon to encounter the brush once in each rotation, a governor for regulating the speed of rotation of said body, and mechanism for controlling the governor from said indicator.

2. In an electric-current interrupter, the combination with a frame and speed-indicator, of a train of gears with actuating means therefor mounted in the frame, a body of insulating material operatively connected with said gears to be rotated thereby, numerically-increasing circuit making and breaking contacts in different annular spaces along said body, a brush at each said space against which said body rotates to cause the contacts thereon to encounter a brush in each revolution of the body, means for switching said brushes individually into and out of the electric circuit, a governor for regulating the speed of rotation of said body, and mechanism for controlling the governor from said indicator.

3. In an electric-current interrupter, the combination with a frame, of a clock-spring-actuated train of gears in said frame terminating in a readily-controllable speed-governor, means on the frame for adjusting the governor to regulate the speed of rotation of the gears, an insulating-cylinder on the shaft of a gear of the train, numerically-increasing circuit making and breaking contact-points in adjacent annular spaces along said cylinder, a brush bearing against each said space, and means for switching the brushes individually into and out of the electric circuit.

4. In an electric-current interrupter, the combination of a casing having a dial, a clock-

spring-actuated train of gears in said casing terminating in readily-controllable speed-governor mechanism, a pointer on the dial operatively connected with said mechanism 5 for controlling the speed of the train in accordance with the indications on the dial, an insulating-cylinder on the shaft of a gear of the train, numerically-increasing circuit making and breaking contact-points in adjacent 10 annular spaces along said cylinder, a brush bearing against each said space, and means for switching the brushes individually into and out of the electric circuit.

5. In an electric-current interrupter, the combination with a frame and speed-indicator, of a train of gears with actuating means therefor mounted in the frame, a body of insulating material formed with a plurality of

separate annular ridges and operatively connected with said gears to be rotated thereby, 20 said ridges being provided, respectively, with numerically-increasing circuit making and breaking peripheral contacts, a brush at each said ridge against which said body rotates to cause the contacts thereon to encounter a 25 brush in each revolution of the body, means for switching said brushes individually into and out of the electric circuit, a governor for regulating the speed of rotation of said body, and mechanism for controlling the governor 30 from said indicator.

JULIUS B. WANTZ.
